UNITED STATES PATENT OFFICE.

ARCHER H. HARRIS, OF BARBERTON, OHIO, ASSIGNOR TO THE FIRESTONE TIRE & RUBBER COMPANY, OF AKRON, OHIO, A CORPORATION OF OHIO.

DEMOUNTABLE RIM.

1,233,465.

Specification of Letters Patent. Patented July 17, 1917.

Application filed May 4, 1916. Serial No. 95,471.

To all whom it may concern:

Be it known that I, ARCHER H. HARRIS, a citizen of the United States, residing at Barberton, in the county of Summit and 5 State of Ohio, have invented certain new and useful Improvements in Demountable Rims, of which the following is a specification.

In the modern form of demountable rim 10 which is extensively used, wedge lugs or wedge rings are forced between the felly band and the rim base and thus hold and center the rim on the wheel. This method of mounting the rim has proven unsatisfactory for several reasons, and it is the purpose of my invention to correct and obviate these evils.

The wedge rings or wedge clamps used in mounting a rim on a felly band, after a considerable use, will become stuck to the felly band and rim by rust and mud, making it quite difficult to remove them in the operation of demounting the rim. Further, the rims are apt to squeak particularly when 15 held on by wedge clamps and not a continuous ring. In the construction herein shown, each objection has been obviated.

The drawings accompanying this specification and forming a part hereof in which 20 like reference numerals refer to like parts:

Figure 1, is a cross section of a rim mounted in place by my improved clamping ring.

Fig. 2, is a front view of the clamping mechanism removed from the rim.

Fig. 3, is a fragmentary perspective view 25 of a felly and felly band showing one of the seats for the clamp.

The construction invented by me comprises a toggle clamp which may be forced 30 in by a nut on a lateral bolt, and upon being forced in exerts a considerable pressure tending to force the rim to its final position on the felly band.

In the drawings 1 represents the ordinary 35 wood felly of the wheel and 2 the felly band shrunk or secured in any suitable manner to the outer face of the felly. The felly band comprises a flat portion indicated at 40 3 and an inclined surface or ledge 4 which is arranged at the rear of the wheel with reference to its position on an automobile. A suitable number of transverse bolts 5 are 45 passed through the felly, the heads of the bolts 6 resting against plates 7 at the rear 50 of the felly. A flange 8 may be formed on

the upper part of plate 7 and serves to back up the felly band 2.

The front edge of the felly band 2 may be beveled off at a number of places as shown at 9, the beveled portions corresponding in 55 number and being located over the transverse bolts. To the inclined face 9 in the form shown in the drawings may be attached the under inclined face of a tapering projection 10 formed on a plate 11, the main 60 portion of which is seated against the front side of the felly. At its lower end, the part 11 is bent outwardly as shown at 12 to form a curved seat or fulcrum for the toggle clamps to be presently described.

If desired, the plate 11 may be formed integral with the felly band 3 either as a continuous flange or as a series of plates, and carries an integral boss or projection 11' received in a socket in the felly and provided with an integral screw threaded bore which is adapted to be mated with the screw threads on the bolt. By this construction 70 the bolt 6 serves as an additional means for holding in and supporting the plate 11. 75

The rim or rim base 13 is formed with a continuous projection or bead 14 on its under surface, the under side of the bead being tapered to correspond to the inclined face 4 of the felly band, the purpose of this 80 construction being to allow the back of the rim a wide bearing space on the felly band. In the front of the rim approximately 85 above the front end of the felly is formed on the under side of the rim a second rib or bead 15. Where the rib or bead rises from the rim base, there is formed a curved socket or fulcrum 16, the purpose of which 90 will presently appear.

The rim shown in the drawings is formed 95 with a gutter 17 at its front side, which is adapted to take a locking ring to hold a removable flange, the type of rim being commonly known as a Q. D. rim. This construction is not essential, however, and the rim can be made as a plain clencher or a straight side if desired.

The rim and felly having been described, I will point out the novel and effective means which I use to center the rim to the 105 wheel. This comprises what might be termed a toggle clamp, which is formed of two members 18 and 19 joined in hinge relation by a pintle 20 being passed through the center of the knuckles 21 and 22 formed 110

integral with the parts 18 and 19 respectively. The lower end of the member 18 is formed rounded as at 23 being adapted to be received in the socket 12 of the plate 5 11. The upper end of the member 19 is formed with two projections 24, the edges of which are curved to closely approximate the curvature of the rim and which are adapted to be received in the socket 16 of 10 the rim base.

The member 18 of the toggle is formed at or near its center with an enlarged boss or bearing portion 25, in the center of which is formed a slot 26 slightly elongated vertically.

The operation of the device will be clear from the foregoing description. In mounting the rim, it is passed over the felly until the bead 14 contacts with the inclined surface 4 of the felly band. The toggle members 18 and 19 which are drawn by the pin 20 to form a complete clamping unit are then set in position with the portion 23 in the socket or fulcrum 12 and the portion 24 25 in the fulcrum 16, the slot 26 being passed over the projected end of a bolt 6. The nut 27 is now threaded on the projecting end of the bolt and each nut about the wheel is tightened equally. By this means the 30 pressure tending to straighten the toggle will exert a positive centering and tightening action on the rim base.

It is obvious that various modifications and changes may be made in the device 35 shown without departing from the spirit of the invention. The specific form of the toggle may be changed and the points to which the power is applied may be altered

from below the knee to the knee and above without affecting the invention.

40

Claims:

1. The combination of a rim, and a wheel of a rim securing means comprising a clamping element, in the form of a toggle operating transversely of the wheel and means for operating the toggle to center and hold the rim on the wheel.

2. The combination of a rim and a wheel structure, a rim securing means comprising a fulcrum on said wheel, a felly band adapted to form a seat for said rim, a toggle lever contacting said wheel structure at said fulcrum only, and means for operating the lever to force the rim to its seat.

3. The combination of a rim, and a wheel provided with a seat for one side of said rim, of a rim securing means comprising a fulcrum at the side of said wheel opposite said seat, a second fulcrum on said rim, a toggle spanning said fulcrums, and means to straighten the toggle to force the rim to its seat.

4. The combination of a rim, and a wheel provided with a seat for one side of said rim, of a rim securing means comprising a fulcrum at the side of said wheel opposite said seat, a second fulcrum on said rim, a toggle spanning said fulcrums, one of the members of said toggle being provided with a slot, a transverse bolt passed through said wheel and said slot, and a nut on said bolt bearing against said member.
